UNITED STATES PATENT OFFICE.

JOHN O. WAGNER, OF CHICAGO, ILLINOIS.

SCREEN FRAME AND SHOE FOR SUPPORTING THE SAME.

Application filed November 1, 1922. Serial No. 598,237.

To all whom it may concern:

Be it known that I, JOHN O. WAGNER, a citizen of the United States, and a resident of the city of Chicago, in the county of Cook and State of Illinois, have invented certain new and useful Improvements in Screen Frames and Shoes for Supporting the Same; and I do hereby declare that the following is a full, clear, and exact description of the same, reference being had to the accompanying drawings, and to the numerals of reference marked thereon, which form a part of this specification.

This invention relates primarily to a screen shoe in which screens of varying width may be retained and from which the screen may be removed by an endwise or vertical movement according to the width of the screen.

In the past, it has been customary to use a shallow guide channel on one side, and a deeper guide channel on the other side to form the shoe, with a spring in the wider guide channel whereby the screen could be removed by an endwise lateral movement. This deep guide was never more than a half inch in depth, so that it was impossible to retain screens of varying width and the screens accordingly had to be manufactured to within one-sixteenth of the size of the window.

It is an object of this invention to overcome the above noted objections, by using a deeper guide channel preferably over an inch in depth and securing the springs to the inner rear walls thereof whereby it is possible to use screens varying as much as three-quarters of an inch or more in width. This construction also provides for any variation arising from the swelling or shrinking of the window frame or settling of the building.

In the past, it has also been customary to provide a frame embodying rockable gripping members for clamping the sheet of foraminous material therein. As constructed this frame could not be readily disassembled nor was the sheet of foraminous material always equally stretched. It is therefore also an object of this invention to provide an improved screen frame which can be readily disassembled and in which the sheet of foraminous material will be equally stretched.

With these and other objects in view, which will become more apparent in the following description and disclosures in the drawings, this invention comprises the novel

structure and combinations hereinafter described and more particularly pointed out and defined in the appended claims.

In the accompanying drawings, which illustrate a preferred embodiment of this invention, and in which similar reference numerals refer to similar features in the different views:

Figure 1 is an elevational view of a window with the screen involving my invention applied thereto.

Figure 2 is an enlarged section upon the line 2—2 of Figure 1.

Figure 3 is an enlarged fragmentary section upon the line 3—3 of Figure 2.

Figure 4 is an enlarged section upon the line 4—4 of Figure 3.

Figure 5 is a section upon the line 5—5 of Figure 4.

Figure 6 is an enlarged sectional view 75 through one side of the screen frame.

Figure 7 is a fragmentary plan view of the front surface of the rockable gripping members within the frame.

In referring now to the drawing, the screen frame is illustrated as consisting of a plurality, four in the present instance, of frame members 1, two of which constitute the sides and two constituting the top and bottom of the frame.

Each frame member is preferably stamped from metal to produce a contour or cross section having terminal outwardly bowed portions 2 and 3 with an intermediate raised or fulcrum portion 4. The outwardly bowed portion 2 is provided with an inwardly extending outer flange 6 which is substantially of arcuate or curved form, except at its free end which has a slight inturned lip 6^a, while the outwardly bowed portion 3 is provided with a marginal lip 7 forming a curved or cam-like approach to the bowed or concave portion 3 so that the front wall of the portion 3 slopes forwardly except at the base of the lip 7.

These frame members have their ends formed to provide miter joints and they are rigidly connected together by angle caps 8 which are stamped or provided with grooves to fit the outer surfaces of the frame members, and screw bolts connect the adjacent frame members to said angle caps. The grooves in the cap pieces that receive the bowed portions of the frame members provide a very rigid joint that prevents all dis-

tortion of the frame or shear upon the screw bolts, so that a very light, rigid and durable screen frame is provided.

Within the screen frame are a plurality 5 of rockable gripper members, one in each side, and one at the top and one at the bottom, which serve to stretch and clamp the foraminous sheet of material 9 to the frame. As these gripper members are of the same 10 general design, only one has been illustrated. Figs. 4 and 6 show the form of rockable gripper member to best advantage. The same consists preferably of a stamped metal plate having an intermediate portion forming 15 a fulcrum 10 resting and rockable upon the fulcrum 4 of the frame, its outer edge being formed into a slight arcuate curl 11 that slidably engages the curved or arcuate flange 6. Its inner edge is formed into a 20 bowed portion having a flange 12 provided with spaced and slight projections 13 (Fig. 7) which in the present instance are stamped outwardly of the flange 12. These projections serve to grip the foraminous sheet of 25 material and insure an even pull and stretching of the same when the rockable gripper members are clamped into operative position.

In Fig. 6 the parts are shown in their 30 inoperative position with a margin of the foraminous sheet 9 extending over the lip 7 and into the inner side of the screen frame. The rockable member is so designed that the inner flange 12 will frictionally enter 35 within the bowed portion 3 of the frame, while the outer curved end or tail 11 will ride inwardly against the flange 6 of the frame. It is therefore evident that by hammering or pressing upon the top of the inner portion of the rockable gripper member 40 with the foraminous sheet upon the lip 7, as shown in Fig. 6, the flange 12 will be forced within the portion 3 and will draw and clamp the margin of the sheet therebetween, 45 while its outer edge end will be elevated against the lip 6. It will of course be understood that the other rockable gripper members are operable in the same manner for clamping the other margins of the 50 screen.

If it is desired at any time to replace the foraminous sheet by a new one, it is only necessary to hammer or exert sufficient pressure upon the outer end of each rockable 55 gripping member to force the same outwardly, thereby raising the front end from its clamping engagement in the frame, the gripping member rocking or pivoting upon its fulcrum 10 during such operation. In 60 constructing the flange 6 with a curved surface and an inner lip against which the outer end of the rockable member presses in its operative position, as shown in Fig. 4, it becomes possible to readily rock the gripping members to their inoperative position,

since the inner surface of the outwardly bowed portion 3 of the frame has a gradual forward slope except at the base of the projecting lip 7 over which the forward end of the rockable member can readily snap. These particular structural features are important in allowing the parts to be disassembled without distorting the same and rendering the same unfit for further service.

The novel form of screen shoe comprises a 70 pair of guide channels 14 and 15 which are removably attached to the sides 16 of the window frame by means of screws or the like. The guide channel 14 is relatively shallow while the guide channel 15 is relatively deep and has the bowed leaf springs 17 fastened at one of their ends to the inner rear wall thereof. The bowed springs 17 are so designed as to project sufficiently forward 80 in the guide channel so that they may press various sizes of screen firmly into the guide channel 14. If the screen is not too wide, it may be removed or inserted in the shoe by an endwise movement as by forcing it in the wide guide channel against the springs 85 until the opposite edge clears the guide channel 14. If it is too wide to thuswise clear the guide channel 14, it may be inserted in or removed from the shoe by sliding 90 it vertically upward out of the shoe as is obvious, the upper ends of the guide channels being left open for this purpose.

It will be apparent that my improved 95 screen shoe may be applied to windows differing in width and nevertheless accommodate and retain the same size of screen, so that it becomes unnecessary to construct the screens to exactly fit the windows but they only need be constructed in standard sizes varying in the neighborhood of one-half of 100 an inch. It will also be apparent that with the use of my improved frame, the sheet of foraminous material is equally stretched and may be readily removed without distorting or damaging the frame.

I am aware that numerous details of construction may be varied through a wide range without departing from the principles of this invention, and I therefore do not purpose limiting the patent granted otherwise than necessitated by the prior art.

I claim as my invention:

1. In a screen frame, a frame member having an intermediate raised fulcrum, an outer arcuate flange with an inwardly extending lip and an inner curved or sloping portion provided with a marginal lip, and a rockable member within said frame member having an intermediate fulcrum resting upon the fulcrum of said frame member, and having an arcuate outer edge in slidably engagement with said arcuate flange and a flanged inner edge adapted to be wedged within said curved portion of said frame member for the purpose described.

2. In a screen frame, a frame member having an intermediate fulcrum, an outer arcuate flange with an inwardly extending lip and an inner curved portion provided with
5 a marginal lip, and a rockable member within said frame member having an intermediate fulcrum resting upon the fulcrum of said frame member and having an arcuate outer edge in slidable engagement with said arcuate flange and a flanged inner edge provided with spaced projections fitting within said inner curved portion of said frame member.

In testimony whereof I have hereunto
subscribed my name.

JOHN O. WAGNER.
